SWING FRAME GRINDER

Charles E. Hite, Philadelphia, Pa., assignor to
 Albert P. De Sanno, Jr., Phoenixville, Pa.

Application October 12, 1940, Serial No. 360,924

15 Claims. (Cl. 51—99)

The present invention relates to swing frame grinders and to the swing suspension, to the operation and to the control of swing frame grinders. The term swing frame grinder in the specification and in the claims means a heavy duty grinder including a frame, a wheel mount and motor carried by the frame toward the forward and rearward ends thereof, a swing suspension support located between the mount and motor and an operating handle or handles extending forward longitudinally beyond the wheel mount for use in strongly pressing the wheel to the work, with the wheel journaled in its mount axially normally horizontal to grind normally on a horizontally horizontal grinder, the structure thus far described being of a type of heavy duty grinder widely used in the prior art.

A purpose of the invention is to avoid shock between the wheel and work.

A further purpose is to resiliently cushion the wheel from inertia—from that of other parts of the machine and from that of the operator pressing upon the machine handles.

A further purpose is to use the weight of the machine in applying pressure between the wheel and work.

A further purpose is to adjustably limit the pressure between the wheel and work.

A further purpose is to continuously indicate the pressure between the wheel and work.

A further purpose is to use variation in pressure between the wheel and work to accomplish one or more or all of the following operations: to stop the motor before the wheel leaves the work; to start the motor after applying the wheel to the work; to sound an alarm whenever the working pressure becomes undesirably high or/and whenever it becomes undesirably low; to stop the motor whenever the working pressure rises above a set high limit or/and whenever it sinks below a set low limit, restarting the motor when the pressure reenters the set pressure range.

A further purpose is to sound high or/and low pressure alarms whenever the pressure is high or low respectively.

A further purpose is to stop the motor automatically whenever the wheel pressure departs from an adjustably predetermined range and to start the motor automatically whenever the wheel pressure reenters the range.

A further purpose is to swing support a swing frame grinder from longitudinally forward and rearward points when not grinding, and when grinding to swing support it at the rearward point 55

while supporting its forward end on the work and wheel.

A further purpose is to raise and lower the front of the machine to and from the work while swing supporting the machine toward the rear.

A further purpose is to extend an arm rearwardly beyond the motor for swing support of the machine from points adjustably distant from the center of gravity of the machine.

A further purpose is to put part of the machine weight on and off the wheel while the wheel is presented to the work.

A further purpose is to suspend the machine adjustably with respect to height from near opposite ends of a trolley rollable along a track, and optionally to pivotally support the track on a second trolley rollable along a second track, with the second track preferably movable laterally.

20 Further purposes will appear in the specification and in the claims.

I have elected to illustrate a few only of the different forms of my invention, illustrating forms however that are practical and efficient in operation and which well illustrate the principles involved.

The drawings are intended to be conventional and in a measure diagrammatic.

Figure 1 is a side elevation to show one embodiment of the invention.

Figure 2 is a broken top plan of Figure 1, in part in section.

Figure 3 is a side elevation of another embodiment, omitting the motor and omitting an optional additional suspension element.

Figure 4 is a broken top plan of Figure 3.

Figure 5 is a broken elevation showing another embodiment of some features of the invention.

Figure 6 is a side elevation of another embodiment.

Figure 7 is a detail section of Figure 6, taken upon the line 7—7 thereof, but with the parts in somewhat different position. In Figure 6 the handles 26³ are undepressed while in Figure 7 they are shown somewhat depressed against the upward retraction of the plate 55', bolt 54, spring 52 and plate 55 across the ends of the forward extensions 56 of the wheel mount.

Figure 8 is a top plan of Figure 6.

Figures 9 and 10 are elevations, to enlarged scale, of alternative contact, indicator and control mechanisms, either being intended for use with any of the embodiments of the preceding figures.

Figures 11 and 12 are diagrammatic elevations

to illustrate suspension features of the invention.

Figures 13 and 14 are sectional elevations of Figures 9 and 10, taken upon the lines 13—13 and 14—14 thereof respectively.

Like numerals refer to like parts in all figures.

Describing in illustration and not in limitation and referring to the drawings:

Each of the illustrated swing grinders broadly is intended to include a grinding wheel 15, a motor 16, body structure 17 and one or more swing elements 18; and work upon which the grinding wheel operates is indicated at 19.

The motor is intended to drive the wheel in any suitable way—conveniently by belt drive—and with the revolution per minute wheel speed preferably selectively variant, either by the use of step pulleys or by a variable speed motor. This drive, where shown at all, is shown conventionally as motor and wheel pulleys 20 and 21 and an intermediate belt 22. It will be understood that the pulleys 20 and 21 may be step pulleys.

In general, the body structure 17 includes a wheel mount 23, 23¹, 23² or 23³ and a supporting frame 24, 24¹, 24² or 24³, the wheel mount hinging at 25, 25¹, 25² or 25³ to the frame, hinging movement between the mount and frame being resiliently resisted by means specific to the particular embodiment of the invention.

In general, the frame 24, 24¹, 24² or 24³ supports the motor 16, is extended forward of the wheel to provide operating handles 26, 26¹, 26² or 26³, receives one or more swing elements 18 and preferably is extended rearward of the motor to receive a rearward swing element 18' at a suitable eye 27 or 27¹ that is preferably adjustable longitudinally of the frame along a portion thereof rearward of the center of gravity of the machine. The forward swing element 18 may be received by the frame at any suitable point thereof forward of, or even at, the center of gravity of the machine, and received either in an eye 28 (Figure 1) rigid with the frame 24 or be received by an inward arm 29 of a shift lever 30 pivoting on a pin 31 rigid with the frame. (Figures 6 and 8.) In these figures the swing element 18 at its lower end hooks under an inward portion of the arm 29.

Referring to Figures 1 and 2, the motor 16, adjustable for belt tension adjustment, is located between adjustment screws 32 and 33 for motor adjustment about a supporting pivot 34. The screws 32 and 33 thread lugs 35 of the frame structure, on a yoke portion 36 thereof upwardly embracing the motor and carrying the pivot pin 34. The pivot pin 34, located at a suitable distance below the motor, is intended to project from opposite sides of the yoke to receive spaced downwardly directed forks of a bracket 35 fastened to the motor. One only of these forks 36 is visible on the drawings.

The suspension eye 27 is intended to be adjustable along the length of a rod 37 carried by upward arms 38 and 39 of the frame at portions thereof rearward and forward of the motor. Optionally the rod 37 and arms 38 and 39 may be omitted and the suspension eye 27 carried on the frame portion 48 rearward of the motor—but the use of the long rod 37 across the motor permits wider adjustment of the eye 27 and thereby of the weight portion deliverable to the wheel and work when the machine is lowered at the forward eye 28 to present the wheel to the work.

The resilient resistance to hinging movement between the wheel mount 23 and the frame 24 in

response to pressure between the wheel and work is applied between opposing upward arms 41 and 42 of the wheel mount and frame respectively and by a spring 43 adjustably compressed against the upper end of the frame arm 42 by a nut and washer 44 on an eye bolt 45 carried by the wheel mount arm 41.

The eye bolt, surrounded by the spring 43, is carried on a pivot pin 46 in the suitably slotted top of the arm 41 and beyond the spring passes the slotted top of the arm 42, a nut 47 beyond the arm 42 adjustably limiting the retraction of the eye bolt and thereby of the wheel mount.

In Figures 3 and 4 the resilient resistance to hinging movement between the wheel mount 23¹ and the frame 24¹ is applied upon an upwardly directed surface of the frame by a flat spring 48 carried by the wheel mount. The spring 48 is suitably fastened at 49 to the wheel mount and retraction of the wheel mount is limited by a rearward arm 50 of the wheel mount coming against an under surface of the frame.

Sometimes, with special conditions or circumstances, a single suspension element 18 may be preferable to two suspension elements and in Figures 3 and 4 I have therefore shown but one suspension element 18 and with a conventional motor mount 51 rearwardly ending the frame 24¹. The mount 51 is intended for any suitable motor mount and it will be understood that the illustrated frames of other figures may omit rearward extension beyond the motor if used with single suspension.

In Figure 5 the resilient resistance to hinging movement between the wheel mount 23² and the frame 24² is applied between opposing upward arms 41' and 42' of the wheel mount and frame respectively and by a tension spring 43' adjustably tensed between a pivot pin 46' in the upper end of the arm 41' and an eye bolt 45' carried adjustably at 46' in the frame arm 42'.

In Figures 6 and 8 the wheel mount 23³, frame 24³ and hinge 25³ are effectively an integral unit, the hinge 25³ comprising a transverse strip of resilient metal connecting the mount and frame members 23³ and 24³.

The "hinge" 25³, whether an insert welded or otherwise fastened to both members 23³ and 24³ or a reduced thickness portion of a single casting making all three members 23³, 24³ and 25³, it should be dimensioned for the intended service—for the needed small resilient bending while presenting all or a portion only of the resilient resistance to the hinging movement.

In the illustration, an adjustable portion of the resilient resistance to hinging movement is intended to be carried by a spring 52 adjustably compressed between a nut 53 on a bolt 54 supported by the frame and the upward surface of a plate 55 carried by the wheel mount 23³ across the forwardly extended ends 56 thereof.

The bolt 54 is supported from upward movement with respect to the frame by a plate 55' below and across the handles 26³ of the frame, optionally dimensionally the same as the plate 55 which is extended to overlap the handles 26³ to limit downward retraction of the wheel mount.

The wheel mount 23³ is intended to carry the upper half of split bearings of the wheel unit and also to carry suitable cover and shield structures, not shown, of the wheel and pulley. The wheel unit is intended to be removable downwardly by the removal of the lower half 57 of the split bearings of the unit.

The shift lever 30 adapted to slightly raise

and lower the frame at 29 to respectively release and apply weight of the machine to the wheel and work, presents a down-bend handle and latch 58 adjacent one of the operating handles 26³.

The shift lever 30 is shown in its weight applying position. The weight is released from the wheel and work by an upward shifting of the down-bend handle 58 to latch over the handle 26³ (Figure 7) after riding the inwardly sloping edge 59 of the down-bend along the outer edge of the member 26³.

A counterbalance spring 60 is intended to balance the lever 30 for easy operation, counterbalancing the weight of the lever and of the machine to any desired extent, the spring 60 being adjustably compressed between the frame 24³ and a nut 61 on a bolt 62 carried by a suitable inward lug from the lever 30, the lug being indicated in dot at 63 and the bolt 62 extending upwardly therefrom loosely through the frame.

The motor 16 is carried on a composite member 64, 65, 66, 67 intended to be suitably bolted to the motor at intervals about the driving end thereof.

The motor mount 64, 65, 66, 67 shields or covers the motor pulley at 64, extends downward at 65 to pivot at 66 in a low lug 68 of the frame 24³ and extends upward at 67 to receive adjustable resilient support for the pull of the motor belt 22. The resilient support for the pull of the belt is provided by a spring 69 compressed adjustably against an upward arm 70 of the frame 24³ by a nut 71 on a threaded eye bolt 72 that is pivotally carried at 73 in the arm 67 of the motor mount, is surrounded by and positions the spring 69 and beyond the spring passes through a suitable slot or bore of the arm 70.

In general, rod and panel members *a* and *b* have been shown on the embodiments thus far described. These members are mounted for relative movement responsive to relative movement of the wheel mount 23, 23¹—23² or 23³ and frame 24, 24¹, 24² or 24³ and are intended for a conventional showing of any suitable mechanism using variation in pressure between the wheel and work to accomplish one or more or all of the following operations: to deenergize the motor before the wheel leaves the work; to energize the motor after applying the wheel to the work; to sound an alarm whenever the working pressure becomes undesirably high or/and whenever it becomes undesirably low; to deenergize the motor whenever the working pressure rises above a preset high limit or/and whenever it sinks below a preset low limit; to reenergize the motor when the working pressure reenters a preset pressure range.

In Figure 1 the rod *a* pivoted at *c* on a rearward extension *d* of the frame arm 42, an upward extension from the frame 24, is presented by gravity or by a suitable spring not shown to the rear end of the eye bolt 45 from the wheel mount 23 for movement thereby across the panel *b* mounted on the frame structure.

In Figures 3 and 4 and also in Figure 5 the panel *b* is mounted on the forward end of the wheel mount 23¹ or 23², is slotted across its width at *e* for easy resilient bending and provided with a resilient bias to maintain it in cooperating relation with the rod *a* mounted on one of the handles 26. The contact members *a* and *b* are in sliding contact, maintained resiliently at *e* and are fastened respectively to the frame 24¹ or 24² and to the wheel mount 23¹ or 23², the spring 48

or 43' resisting deflection between the frame and mount members 24¹ or 24² and 23¹ or 23².

In Figures 6 and 8 the members *a* and *b*, intended to be preferably located between the plates 55 and 55' have been shown immediately forward thereof, with the panel *b* mounted on one or both of the rearward wheelmount extensions 56 and the rod *a* mounted on one of the handles 26¹ or 26². The contact member *a* is thus shown fastened to the frame member 24³ from one of the arms 26³ with the contact member *b* fastened to the wheel mount 23³ across the ends of the arms 56.

I have illustrated two embodiments only of the cooperating rod and panel mechanisms *a* and *b*, in Figures 9 and 10 respectively. An electric grounding circuit *f*, *g* shown applied to the rod and panel mechanisms *a*₁ or *a*₂ and *b*₁ or *b*₂ in Figures 9 and 10 is intended for a conventional showing of any circuit adapted to control the operation of the motor 16 or/and that of an electric alarm *h*. The composite rod and panel members *a*₁ or *a*₂ and *b*₁ or *b*₂ are intended to be supported respectively at *i* and *j*, suitable portions of the machine respectively on the resiliently connected wheel mount and frame and thereby relatively movable in response to changing pressure between the wheel and work transmitted through the wheel and its resilient connection with the frame and transmitted resiliently between the frame and work.

In the illustrations of Figures 1 to 8 the cooperating contact members *a* and *b* are carried cooperatively by the mount and frame members 23 and 24, with the members *a* and *b* resiliently in sliding contact one with the other and in relative positions determinatively responsive to the pressure between the wheel and work, and any of many mechanisms may be carried cooperatively by the members *a* and *b*, suitably the pointer-and-scale indicator 83, 76 or 83', 76' of Figure 9 or of Figure 10.

In Figure 9, the composite "rod" mechanism *a*₁, suitably supported from the machine at *i*, includes a flat spring 74 at or near its supported end and an arm 75 therefrom preferably of insulation material. The arm 75 carries at intervals of its length an indicator 76, adjustable screw contacts 77, 78, 79, 80 and 81 and the electric signal *h*.

The composite panel *b*₁, suitably supported at *j*, comprises an insulation plate 82, a scale 83 and a contact plate 84.

The scale 83 and contact plate 84 are adjustably fastened at 85 and 86 respectively to the plate 82, respectively to present the scale 83 in best cooperative relation with the indicator 76 and contact surfaces 87, 88, 89, 90 and 91 in best cooperative relation with the inwardly directed ends of the screw adjustment contacts 77, 78, 79, 80 and 81 respectively. Only the insulation heads of the screw contacts 77 to 81 are visible in the drawing; their inwardly directed contact ends are presented inward to extents individually adjustable at the insulation heads of the contacts.

Of the contact surfaces 87 to 91, the surface 91 is intended to be parallel to the direction of movement of the panel *b*₁ and during the desired range of pressure between the wheel and work the normal operating circuit is closed through the members *f*, 81, 91, *g*.

The surfaces 89 and 90 slope in reverse directions with respect to the direction of movement of the panel *b*₁ to cooperate with the signal circuit contacts 79 and 80 and these screw contacts

79 and 80 are adjusted to engage their respective cooperating surfaces 89 and 90 at any desired wheel pressures.

With rising wheel pressure above any preset limit the wedge surface 89 engaging the screw contact 79 deflects the arm 75 outward against the retraction of the spring 74, opening the normal motor control circuit f, 81, 91, g operating the high pressure signal through the signal and motor control circuit f, h, 79, 89, 91, g. If in response to the signal the wheel pressure is reduced to the preset range the arm 75 retracts inward until stopped by the screw contact 81 engaging the contact surface 91, closing the normal motor control circuit f, 81, 91, g and then with further reduction of wheel pressure opening the circuit f, h, 79, 89, 91, g in that the wedge 89 is then in a position at which it cannot engage the contact 79.

The operation of the low pressure signal is exactly similar, the low pressure signal operating through the signal and motor control circuit f, h, 80, 90, 91, g as soon as the wheel pressure sinks below any preset low limit.

In similar manner deenergizing the motor may be effected automatically at any desired high and low limits of wheel pressure by suitably adjusting the screw contacts 77 and 78 with respect to their cooperating reverse wedge contacts 87 and 88 which are suitably steeper than the wedge contacts 89 and 90. Adjustments are conveniently effected while applying the high and low limit pressures beyond which it is deemed undesirable for the motor to operate.

In Figure 10 the rod a₂ comprises a resilient conductor 75', an adjustable screw contact 81' and an indicator 76', and the panel b₂ comprises an insulation base plate 82', the signal h, the scale 83', adjustable high and low pressure wedge signal contacts 89' and 90' and adjustable high and low pressure cut-out wedges 87' and 88' that are suitably steeper than the contacts 89' and 90'.

In normal operation the screw contact 81' is presented to the non-sloping contact 91' closing a motor control circuit f, 91', 81', 75', g. The high pressure signal operates when with rising wheel pressure the wedge contact 89' engages the resilient conductor 75' wedging it outward to open the motor control circuit f, 91', 81', 75', g while closing the signal circuit f, h, 89', 75', g which with further rise of wheel pressure will be opened at any desired point by the suitably set steeper wedge 87'. The low pressure signal and the low pressure cut-out are effected in similar and obvious manner by means of the low pressure signal contact 90' and the steeper low pressure cut-out contact 88'.

In Figures 1 and 2 relative movement of the members a and b is multiplied by lever structure while in each of Figures 3, 4, 5 and 6, 8 the members a and b are fastened one to the wheel mount 23¹, 23² or 23³ and the other to the frame 24¹, 24² or 24³. In Figures 9 and 10 the members a₁ and b₁ and a₂ and b₂ are shown carried cooperatively between the frame and mount by conventionally shown structures i and j, intended to be any suitable structures between the frame and mount. In Figures 1 and 2 i may be considered as the upper portion of the member a responsive connected to the wheel mount 23 through the eyebolt 45 while j may be a suitable extension from or portion of the frame 24. In each of Figures 3, 4, 5 and 6, 8 the structures i and j are

portions one of the wheel mount 23¹, 23² or 23³ and the other of the frame 24¹, 24² or 24³.

I illustrate in Figures 11 and 12 too only of the suitable overhead supporting structures of the grinder.

The grinder depends on the suspension elements 18 and 18' from near opposite ends of a suitable trolley 92 or 92' and with hoists 93 and 93' directly beneath the trolley permitting the grinder to be raised and lowered easily and to any desired extent at points forward and rearward of the center of gravity of the grinder.

In Figure 11 the forward suspension element is intended to have been located but a little forward of the center of gravity of the machine to shorten the spacing between the suspension elements with a resultant lessening of the needed length of the trolley 92. In many cases however it may be desirable to locate the forward suspension element well forward in order to bring the hoist 93 near to the operating end of the machine.

In Figure 12 the trolley 92' is shown rollably supported on a track 94', suitably of I-beam section and either stationary or laterally movable according to operating requirements.

The overhead structure of Figure 11 provides for universal shifting of the machine for operation anywhere over a relatively wide floor space. The short track 94 supporting the trolley 92 is provided with end guards 95 and is provided with vertical pivot support at 96 from the bottom of a second trolley 97 that is supported by and rollable along a second track 98.

The second track 98 is intended to be movable laterally, as indicated by the arrow.

It has been found that grinding economy is materially dependent upon the use of right pressures between the wheel and work and these vary both with the character of the work and the character of the wheel, as to grade and material from which the work has been made, and my invention, particularly in its features eliminating wheel shock, in disclosing the operating pressure, in signaling any departure from predetermined right pressure ranges and in deenergizing the wheel when this departure is too great, should result in great economies in grinding.

In view of my invention and disclosure variations and modifications will doubtless become evident to others skilled in the art either to meet individual whim or particular circumstance and I claim all such in so far as they fall within the reasonable spirit and scope of the invention.

In the structure of Figures 1 and 2 the member 39, 37, 38 is intended to comprise a yoke rotatable at 38' and 39' on the frame to permit easy angular vertical turning of the grinder for operation of the grinder with the wheel at different angles to the vertical.

Having thus described my invention what I claim as new and desire to secure by Letters Patent is:

1. A swing frame grinder, elongated, operating generally horizontal, having intermediate its length a swing support to adapt it to back and forth grinding travel in direction of its length and laterally thereof, and the grinder comprising an elongated forwardly and rearwardly directed frame, a motor on the frame toward its rearward end, a grinding wheel operable by the motor and located toward the forward end of the frame, a wheel mount journaling the wheel, a hinge connection between the mount and frame with the line of hinging located rearwardly of the wheel axis, an upward arm on the mount from the line

of hinging, an upward arm on the frame opposing the first arm and spaced therefrom in the direction of the frame length and a resilient connection between the arms at opposing upper portions thereof permitting sudden vertical resilient movements between the wheel and frame during grinding.

2. A swing frame grinder, elongated, operating generally horizontal, having intermediate its length a swing support to adapt it to back and forth grinding travel in direction of its length and laterally thereof and the grinder comprising an elongated forwardly and rearwardly directed frame, a motor on the frame toward its rearward end, a grinding wheel operable by the motor and located toward the forward end of the frame, a wheel mount journaling the wheel, a resilient supporting connection between the frame and mount permitting sudden vertical resilient movements between the wheel and frame and means effective towards the forward end of the frame for downwardly pressing the frame to press the wheel to the work through the resilience of the said connection and means for adjusting the resilience between the wheel mount and frame.

3. A swing frame grinder, elongated, operating generally horizontal, having intermediate its length a swing support to adapt it to back and forth grinding travel in direction of its length and laterally thereof and the grinder comprising an elongated forwardly and rearwardly directed frame, a motor on the frame toward its rearward end, a grinding wheel operable by the motor and located toward the forward end of the frame, a wheel mount journaling the wheel, a resilient supporting connection between the frame and mount permitting sudden vertical resilient movements between the wheel and frame and means effective towards the forward end of the frame for downwardly pressing the frame to press the wheel to the work through the resilience of the said connection and means for adjusting the resilience between the wheel mount and frame.

4. A swing frame grinder, elongated, operating generally horizontal, having intermediate its length a swing support to adapt it to back and forth grinding travel in direction of its length and laterally thereof and the grinder comprising an elongated forwardly and rearwardly directed frame, a motor on the frame toward its rearward end, a grinding wheel operable by the motor and located toward the forward end of the frame, a wheel mount journaling the wheel, a resilient supporting connection between the frame and mount permitting sudden vertical resilient movements between the wheel and frame and means effective towards the forward end of the frame for downwardly pressing the frame to press the wheel to the work through the resilience of the said connection and the grinder having a determinative electric circuit and having switch contacts thereof operated by the mount and frame in order to determine the condition of the circuit by the relative positions of the mount and frame and thereby according to the pressure between the wheel and work.

5. A swing frame grinder, elongated, operating generally horizontal, having intermediate its length a swing support to adapt it to back and forth grinding travel in direction of its length and laterally thereof and the grinder comprising an elongated forwardly and rearwardly directed frame, a motor on the frame toward its rearward

end, a grinding wheel operable by the motor and located toward the forward end of the frame, a wheel mount journaling the wheel, a resilient supporting connection between the frame and mount permitting sudden vertical resilient movements between the wheel and frame and means effective towards the forward end of the frame for downwardly pressing the frame to press the wheel to the work through the resilience of the said connection, a signal, an electric circuit to operate the signal and a switch of the circuit operatively connected to the mount and frame to operate the signal by the position of the frame with respect to the mount and thereby according to the pressure between the wheel and work.

6. A swing frame grinder, elongated, operating generally horizontal, having intermediate its length a swing support to adapt it to back and forth grinding travel in direction of its length and laterally thereof and the grinder comprising an elongated forwardly and rearwardly directed frame, a motor on the frame toward its rearward end, a grinding wheel operable by the motor and located toward the forward end of the frame, a wheel mount journaling the wheel, a resilient supporting connection between the frame and mount permitting sudden vertical resilient movements between the wheel and frame and means effective towards the forward end of the frame for downwardly pressing the frame to press the wheel to the work through the resilience of the said connection and means operatively connected to the mount and frame for energizing and de-energizing the wheel according to the position of the frame with respect to the mount and thereby according to the pressure between the wheel and work.

7. A swing frame grinder, elongated, operating generally horizontal, having intermediate its length a swing support to adapt it to back and forth grinding travel in direction of its length and laterally thereof and the grinder comprising an elongated forwardly and rearwardly directed frame, a motor on the frame toward its rearward end, a grinding wheel operable by the motor and located toward the forward end of the frame, a wheel mount journaling the wheel, a resilient supporting connection between the frame and mount permitting sudden vertical resilient movements between the wheel and frame and means effective towards the forward end of the frame for downwardly pressing the frame to press the wheel to the work through the resilience of the said connection, an electric circuit energizing the wheel and wedge-adjustable-means operatively connected to the mount and frame for opening and closing the circuit according to the adjustably selective position of the frame with respect to the mount and thereby according to the adjustably selective pressure between the wheel and work.

8. A swing frame grinder, elongated, operating generally horizontal, having intermediate its length a swing support to adapt it to back and forth grinding travel in direction of its length and laterally thereof and the grinder comprising an elongated forwardly and rearwardly directed frame, a motor on the frame toward its rearward end, a grinding wheel operable by the motor and located toward the forward end of the frame, a wheel mount journaling the wheel, a resilient supporting connection between the frame and mount permitting sudden vertical resilient movements between the wheel and frame and means effective towards the forward end of the frame for downwardly pressing the frame to press the wheel to the work through the resilience of the said connection, a signal, an electric circuit to operate the signal and a switch of the circuit operatively connected to the mount and frame to operate the signal by the position of the frame with respect to the mount and thereby according to the pressure between the wheel and work.

wheel to the work through the resilience of the said connection, an electric circuit energizing the wheel and wedge-means operatively connected to the mount and frame for opening and closing the circuit according to the position of the frame with respect to the mount and thereby according to the pressure between the wheel and work.

9. A swing frame grinder, elongated, operating generally horizontal, having intermediate its length a swing support to adapt it to back and forth grinding travel in direction of its length and laterally thereof and the grinder comprising an elongated forwardly and rearwardly directed frame, a motor on the frame toward its rearward end, a grinding wheel operable by the motor and located toward the forward end of the frame, a wheel mount journaling the wheel, a resilient supporting connection between the frame and mount permitting sudden vertical resilient movements between the wheel and frame and means effective towards the forward end of the frame for downwardly pressing the frame to press the wheel to the work through the resilience of the said connection, an electric circuit to energize the wheel and reversely sloping wedge means operatively connected to the mount and frame to operate the opening and closing of the circuit at low positions of the frame with respect to the mount by means of one wedge and at high positions of the frame with respect to the mount to operate the opening and closing of the circuit by means of a reversely sloping wedge, thereby to maintain the wheel energized as long as the pressure between the wheel and work is between high and low pressure limits determined by the said means and de-energized when the pressure between the wheel and work is above the high limit and de-energized when the pressure between the wheel and work is below the low limit.

10. A swing frame grinder comprising an elongated generally horizontal forwardly and rearwardly directed frame, a motor on the frame toward the rearward end thereof, a grinding wheel operable by the motor, a handle forwardly of the wheel for downwardly pressing and forwardly and rearwardly moving the wheel on the work, a suspension element from a portion of the grinder located along the grinder at or forward of the center of gravity of the grinder and for use during periods of non-grinding and a second suspension element from a portion of the grinder rearward of the center of gravity, for use during grinding periods with the first element then inoperative and the weight of the machine supported between the work and rearward element, making part of the machine weight effective for grinding pressure between the wheel and work and means operable at the handle for shifting the machine vertically at one of the suspension elements to raise and lower the wheel from and to the work.

11. In a swing frame grinder, a suspension element located adjustably rearward of the center of gravity of the grinder and a second suspension element at or forward of the center of gravity whereby when not grinding the weight of the machine is supported normally on the two suspension elements and whereby during periods of grinding the weight of the machine may be carried between the work and a suspension element located adjustably to the rear of the center of gravity, thereby making an adjustable portion of the weight effective for grinding pressure between the wheel and work.

12. In a swing frame grinder, a wheel mount, a frame, a resilient connection between the mount and frame and suspension elements located at points on the frame respectively rearward of and at or forward of the center of gravity of the grinder whereby when not grinding the weight of the machine is supported normally on the two suspension elements and whereby during periods of grinding the weight of the machine may be carried between the work and rearward suspension element making a portion of the weight of the machine effective for grinding pressure and whereby the resilience between the wheel and frame cushions the greater inertia of the machine from the wheel, the machine inertia increasing with increasing distance of the rearward suspension element from the center of gravity of the machine.

13. In a swing frame grinder, a wheel mount, a frame, a resilient connection between the mount and frame, an operating handle, suspension elements on the frame located at points thereof respectively rearward of and at or forward of the center of gravity of the grinder and means operable at the handle and adapted to slightly raise and lower the grinder at the forward suspension element to raise and lower the wheel to the work, whereby when the wheel is lowered to the work the machine weight is carried between the work and rearward suspension element making a portion of the machine weight effective for grinding pressure, and whereby when the wheel is raised the weight of the machine is carried between the two suspension elements.

14. A swing frame grinder comprising an elongated forwardly and rearwardly directed frame, a motor on the frame toward the rearward end thereof, a grinding wheel operable by the motor and located toward the forward end of the frame, a handle forwardly of the wheel for downwardly pressing and forwardly and rearwardly moving the wheel on the work, a forwardly and rearwardly directed arm located above and across the motor and downwardly connected with the frame, and a suspension element adjustable along the arm, adapting the grinder toward its forward end supported on the wheel and work to be moved at the handle back and forth in direction of the grinder length and laterally thereof with an adjustable portion of the weight of the machine effective for pressure between the wheel and work.

15. A swing frame grinder comprising an elongated forwardly and rearwardly directed frame, a motor on the frame toward the rearward end thereof, a grinding wheel operable by the motor and located toward the forward end of the frame, a handle forwardly of the wheel for downwardly pressing and forwardly and rearwardly progressing the wheel on the work, a yoke downwardly embracing the motor, having downward arms respectively forward and rearward of the motor, coaxial pivot connections between the downward arms and frame to provide an axial pivot support for the machine during grinding and a suspension element on the yoke, whereby during grinding the weight of the machine is carried between the work and suspension element, making the weight portion on the work effective for grinding pressure and whereby the machine may be angularly turned in the pivot between the frame and yoke to apply the wheel at an angle to the vertical.
